UNITED STATES PATENT OFFICE.

WILFRED E. TAIT, OF BOSTON, MASSACHUSETTS, ASSIGNOR TO ISIDOR SHULMAN AND MEYER SHULMAN, COMPOSING THE FIRM OF SHULMAN & SONS, OF NEW YORK, N. Y.

PERMUTATION LOCK.

Application filed July 21, 1926. Serial No. 123,838.

This invention relates to improvements in permutation locks, and especially to that class of locks adapted to be used in connection with document boxes, miniature safes, cash drawers and the like.

The main object of the invention is to provide a lock of this character positive in action and simple and inexpensive in construction.

Another object of this invention is to provide a lock of this character in which a large number of permutations or changes of combinations may be had with the same device by merely changing the relative position of some of the parts of the lock.

Other objects and novel features of construction will become apparent as the specification proceeds.

In the drawings forming a part of this specification,

Fig. 1 is a front view in elevation of a miniature bank with my improved lock applied thereto.

Fig. 2 is a sectional view taken on line 25 2—2 Fig. 4.

Fig. 3 is a similar view to Fig. 2 but with the lock in open position.

Fig. 4 is a sectional view on line 4—4 Fig. 1.

Figs. 5 and 6 are detail views of one of the tumbler disks.

Figs. 7 and 8 are detail views of the other disk and

Fig. 9 is a fragmental sectional view showing how the disks are connected to each other.

Referring to the drawings in detail in which like reference characters denote the same parts throughout the different views, 40 10 denotes the body portion of a bank or receptacle provided with a door or plate 11 hingedly connected to the body portion at 12. The body 10 is provided with a projection 13 at the opposite side of the hinge 12 and the projection 13 has a recess or opening 14 therein to accommodate one end of a bolt 15 slidably mounted in the door 11 by means of a stud 16 secured in the bolt 15 and passing through a slot 17 in the door 11.

45 Centrally located on the door 11 there is a hole or opening 18. A disk or tumbler 19 is mounted for rotation on the door 11 by means of a shoulder 20 on the said disk ex-

tending into the opening 18. A second tumbler or disk 21 is rotatively mounted on a shoulder 22 of the disk 19. Riveting eyelets 23 passing through the disk 19 slightly overlie one surface of the disk 21 and tend to maintain the disks 19 and 21 in frictional engagement with each other. The disk 19 carrying the disk 21 thereon is removably mounted on a stud 25 having a regular polygonal cross section. The disk 19 is provided with a hole 25^a having the same contour as the cross section of the stud 25. A dial plate 26 having alphabetical markings 27 thereon is secured on a shoulder 28 of said stud 25 between the door 11 and a knob 29 securely mounted on a reduced portion 30 of the stud 25. A spring strip 31 removably fitting in an annular groove 32 in the stud 25 maintains the disks 19 and 21 on the stud 25 in resilient engagement with the door 11. A pin 34 projecting inwardly from the door 11 coacts with a pin 35 projecting from the disk 21 to bring the disks 19 and 21 into proper alignment when operated open the lock.

To operate the lock to an open position, the knob 29 carrying the dial plate 26, stud 25 and the disks 19 and 21 is turned twice in a clockwise direction until a predetermined letter on the dial plate comes in line with an arrow 36 on the door 11, and then the knob is turned in the opposite direction to a predetermined point, when notches 37 and 38 in the disks 19 and 21 respectively will be directly in line with the bolt 15. The door is then pulled outwardly by the knob 29 and a cam surface on the bolt 15 pressing against the front edge of the recess 14 will cause the said bolt to ride into the notches 37 and 38 and the door will then swing open.

In the present instance the combination for opening the lock consists of turning the knob and dial in a clockwise direction until the letter B on the dial is in line with the arrow, and then back to the letter N when the door may be swung open.

It will be understood that as the knob is turned in a clockwise direction to destroy the setting indicated in Fig. 3 which is the open position, both of the disks will revolve in unison until the letter B is in line with the arrow, and then back to the letter N when the arrow, and the pin 35 in the disk 21 will

come in contact with the pin 34 in the door, which contact will arrest the further movement of the disk 21 and further revolution of the knob will revolve the disk 19 only, 5 until the letter B on the dial has come in alinement with the arrow a second time at which time the notches are again overlying each other and as the knob is turned in the opposite direction the disks will again move 10 in unison until the said notches are in line with the bolt 15, when the door may be opened by pulling on the said knob.

It will also be seen from Fig. 3 that when the bolt 15 is in the notches the knob can 15 only be rotated in the direction indicated by the arrows in Figs. 1 and 3, as the notches 37 and 38 are provided with locking surfaces 39 and 40.

By removing the spring 31, the disks may 20 be lifted from the stud 25 and replaced in a different relative position thereon, thus changing the combination which will open the said lock. By using a stud of hexagonal cross section, six different combinations may 25 be obtained at will. In the manufacturing of this device however, numerous other combinations may be had by altering the positions of the pin 34 in the door, or the pin 35 in the disk 21.

30 From the foregoing, it will be seen that I have provided a lock simple in construction, positive in action and one in which numerous changes of combinations may be had both in the manufacturing of the lock 35 and by the owner of such a lock after it is manufactured.

40 In the drawings, I have illustrated a preferred form of my invention, but I do not restrict myself to this form, as many modifications and changes may be made without departing from the scope of the appended claims.

Having described my invention, what I 45 claim as new is:

45 1. A permutation lock, comprising a plate having an opening therein, a notched disk having a polygonal opening therein, a shoulder on said disk, a second notched disk revolvably mounted on said shoulder, connecting means on one of the disks for frictionally maintaining the other disk thereon, a polygonal stud passing through the openings in the plate and the first mentioned disk, a resilient member associated with the 50 stud and disks, and a bolt in operative engagement with the disks and slidably mounted on the plate.

60 2. In a permutation lock, a polygonal stud, a notched disk removably mounted on said stud, a second disk rotatably mounted on the first mentioned disk, means on one of the disks for frictionally maintaining the said disks in sliding engagement with each other, a resilient member in engagement with 65 the first mentioned disk removably mounted

on the said stud, a slidable bolt on the plate in operative engagement with the disks and means on the said disks to insure their rotation in a predetermined direction to actuate the bolt into locking position.

70 3. In a receptacle, a permutation lock, comprising a plate hingedly mounted on said receptacle, a notched disk revolvably mounted in said plate, a polygonal stud passing through the said disk, a second disk 75 rotatably mounted on the first mentioned disk, means associated with the said disks to frictionally maintain them in operative engagement with each other, a bolt in operative engagement with the said disks and 80 slidably mounted on the plate and partly projecting into a recess of the receptacle, a pin on the second mentioned disk, a projecting pin on the plate in the path of the pin in the disk and a knob on the stud whereby the disks may be rotated and brought into proper alinement by the said pins to a position where the bolt may be withdrawn from the recess and the plate swung open.

85 4. In a receptacle a permutation lock, comprising a plate hingedly mounted on said receptacle, a notched disk revolvably mounted in said plate, a polygonal stud passing through the said disk, a second disk rotatably mounted on the first mentioned disk, means associated with the said disks to frictionally maintain them in operative engagement with each other, a bolt in operative engagement with the said disks slidably mounted on the plate and partly projecting into a recess of the receptacle, a pin on the second mentioned disk, a projecting pin on the plate in the path of the pin in the disk, a knob on the stud whereby the disks may be rotated and brought into proper alinement by the said pins to a position where the bolt may be withdrawn from the recess and the plate swung open, and a resilient member 90 removably mounted on the stud and in engagement with the first mentioned disk to maintain same in yielding engagement with the plate.

100 5. A permutation lock, comprising a plate having an opening therein, a notched disk having a polygonal opening therein, a shoulder on said disk, a second notched disk revolvably mounted on said first mentioned disk, a polygonal stud passing through the openings in the plate, and the first mentioned disk, a resilient member associated with the stud and disks, a bolt slidably mounted on the plate operated by the said disks and a locking surface on each of the notches of the disks to prevent the said disks from being rotated in the wrong direction.

105 In testimony whereof I hereunto affix my signature,

WILFRED E. TAIT.
